UNITED STATES PATENT OFFICE.

OTIS R. ANGELL, OF BRADFORD, MASSACHUSETTS.

SOLE-EDGE SETTER.

1,278,287.

Specification of Letters Patent. Patented Sept. 10, 1918.

Application filed June 1, 1918. Serial No. 237,772.

To all whom it may concern:

Be it known that I, OTIS R. ANGELL, a citizen of the United States, residing at Bradford, in the county of Essex and State 5 of Massachusetts, have invented certain new and useful Improvements in Sole-Edge Setters; and I do declare the following to be a full, clear, and exact description of the invention, such as will enable others 10 skilled in the art to which it appertains to make and use the same.

My invention relates to improvements in machines employed for setting or burnishing the edges of shoe soles, and one object 15 is to provide a machine of this class in which the burnishing tools have movement in one plane only, rather than traveling on an arc as heretofore.

A further object of the invention is to 20 provide a pair of burnishing tools for use on different parts of the sole, and to make provision whereby either of said tools may be brought into play while the machine is in operation.

With the foregoing objects in view, the 25 invention resides in the novel features of construction and unique combinations of parts to be hereinafter fully described and claimed, the descriptive matter being supplemented by the accompanying drawings 30 which form a part of this application and in which:

Figure 1 is a side elevation of the machine partly in section;

Fig. 2 is a vertical transverse section of 35 the plane of the line 2—2 of Fig. 1;

Fig. 3 is a detail front elevation of the tool carrying head and associated parts;

Fig. 4 is a detail horizontal section on 40 the line 4—4 of Fig. 1; and

Fig. 5 is a side elevation of one of the bearing carrying plates.

In the drawings above briefly described, 45 the numeral 1 designates the vertical standard of a sole edge setting machine, the upper end of said standard having a hollow head 2 provided at one end with a substantially rectangular casing 3 whose outer end is closed by a removable plate 50 4, said plate having an opening 5 through which a downwardly curved arm 6 projects to carry the burnishing tools. The inner end of arm 6 is joined to one side of a substantially rectangular block 7

mounted for horizontal reciprocation in the 55 casing 3, the upper and lower edges of said block being shown provided with V-shaped grooves 8 which receive therein similarly shaped tracks 9, said tracks bearing against the top and bottom of the casing 3 and having vertically extending pins 10 near their ends received slidably in openings 11 formed in said top and bottom. The lower track 9 is secured rigidly against the bottom of the casing by a central screw 60 12, while a central adjusting screw 13 is provided for retaining the upper track 9 snugly in engagement with the sliding block 7, said set screw being provided with a suitable lock nut 14.

The side of block 7 opposite the arm 6, is provided with a preferably rectangular socket 15 having parallel vertical side walls 16, said socket receiving therein a second 70 rectangular block 17 provided with vertical edges engaging the side walls 16 of said socket, said edges of the block 17 each having a vertically elongated recess 18. Rectangular plates 19 are snugly received in the recesses 18 and carry ball or other 80 appropriate anti-friction bearings 20 which travel on the side walls 16 of socket 15.

Adjacent its center, the block 17 is provided with an opening 21 in which is positioned the ball bearing 22, said bearing receiving therein an eccentric wrist pin 23 on the end of a horizontal drive shaft 24 which is mounted rotatably in the head 2 and extends into the casing 3. By this arrangement, as shaft 24 rotates, the block 90 17 will reciprocate vertically in the socket 15 and the block 7 will be horizontally reciprocated to similarly move the tool carrying arm 6, particular emphasis being laid upon the fact that this arm moves back and forth on a straight line rather than on an arc.

Preferably employed in connection with the features so far described, is a metal disk 25 which is secured on the end of shaft 100 24 adjacent the inner sides of the two blocks 7 and 17. The lower end of the casing 3 is adapted to contain lubricating oil, and by providing the disk 25, this oil will be continually thrown over the moving parts of the device, thus insuring easy and approximately noiseless operation thereof. Furthermore, little vibration takes place in

comparison to machines which have heretofore been used.

The free end of arm 6 is provided with a vertical bearing 26 whose lower end is enlarged at 27 and provided with a transverse groove 28. A tool holding head 29 is movable bodily with the bearing 26 and is provided on its upper end with a transverse rib 30 received normally in the groove 28 to prevent rotation of the head. The burnishing tools 31 and 32 are detachably secured to the lower end of the head 29 by suitable spring detents 33 and by turning the head a half revolution, either of said tools may be brought into operative relation with the work rest R which may be of the usual or any preferred design.

Above the arm 6, the end plate 4 of casing 3 is provided with an integral supporting arm 34 having in its outer end a socket 35 receiving a lateral stud 36 on a substantially vertical bearing 37 which is aligned with the bearing 26, a set screw 38 and groove 39 being provided to retain the stud 36 in the socket 35, and at the same time to permit rocking of said stud. A flexible shaft 40 is rotatably mounted in the two bearings 26 and 37 and is connected operatively with the head 29 for rotating the latter while the machine is in operation, to bring either tool 31 or 32 into play. In the present embodiment of the invention, the shaft 40 is formed of a lower section 41 rotatable and slidable in the bearing 26, an upper section 42 slidable and rotatable in the bearing 37, and a connection between the two sections, the lower section 41 being joined to the head 29, while the upper section is provided with an operating knob 43. Suitable coiled springs 44 are provided for the two sections 41 and 42 to normally shift them upwardly so as to engage the rib 30 with groove 28, to hold the head 29 in adjusted position. By pushing downwardly on the head 43 however and turning the same, the locking means 28-30 are released and the head rotated to bring the proper tool into play. Release of the knob then permits the springs 44 to return the several parts to normal locked position.

The aforementioned connection between the two shaft sections 41 and 42 might well be embodied in a number of forms, but I prefer to provide said section 41 with a head 45 having a V-shaped socket 46 in its upper end receiving the similarly shaped lower end 47 of shaft section 42, the opposite sides of said end being flattened so that they may slide upon the sides of the socket 46 but may not rotate in respect thereto. The socket 46 is of sufficient dimensions to permit horizontal reciprocation of the tool carrying head 29 without continually oscillating the upper shaft section 42, and although this section will be rocked to and fro when said head is turned a quarter of a revolution, the move-

ment will not be undesirable to the operator, due to the fact that the knob 43 is located in close proximity to the axis upon which the bearing 37 rocks, the movement of said knob being therefore slight.

From the foregoing, taken in connection with the accompanying drawings, it will be obvious that although I have provided a comparatively simple sole edge setting machine, the same will be highly efficient and in every way desirable, particular emphasis being laid upon the novel operating means for the arm 6 and upon the flexible shaft 40 for adjusting the tool carrying head 29 as required to bring either tool 31-32 into play. One of these tools is used on the front portion of the sole and the other on the instep part thereof.

Since probably the best results are obtained from the several details shown and described, they are by preference followed, but within the scope of the invention as claimed, considerable latitude is allowed for making such minor changes as occasion may dictate.

I claim:

1. A sole edge burnisher comprising a block mounted for horizontal reciprocation and having in one side a socket with parallel vertical side walls, an arm extending from the other side of said block and carrying a burnishing tool, a second and vertically reciprocating block received in said socket and having two vertical edges each provided with a vertically elongated recess, a pair of vertical plates disposed snugly in said recesses carrying anti-friction bearings contacting with said side walls of the socket, said second block having an opening, and a drive shaft having an eccentric wrist pin mounted in said opening.

2. A sole edge burnisher comprising a block carrying a burnisher and having grooves in its upper and lower edges and a socket opening through one of its sides, a pair of tracks received in said grooves to mount said block for horizontal reciprocation, a casing in which said block and tracks are located, the top and bottom of said casing having openings adjacent the ends of said tracks, vertical pins extending from said tracks and received in said openings, a screw securing the lower track against the bottom of the casing, an adjusting screw for retaining the upper track snugly in its respective groove, a second block slidable vertically in said socket and having an opening, and a drive shaft having a wrist pin mounted in said opening.

3. A sole edge burnisher comprising a block carrying a burnisher and having grooves in its upper and lower edges and a socket opening through one of its sides, a pair of tracks received in said grooves to mount said block for horizontal reciproca-

- tion, a casing in which said block and tracks are located and to which said tracks are secured, a second block slidable vertically in said socket and having an opening, a drive shaft extending into said casing and having a wrist pin mounted in said opening, and a disk secured on said shaft at the inner sides of said blocks, whereby to throw oil from the casing over the moving parts.
- 10 4. A sole edge burnisher comprising a proceeding and receding support, a tool holder movable bodily with said support and rotatable on an axis transverse to the travel thereof, a second and fixed support spaced from the other, and a flexible shaft extending between the two supports for turning said holder while the machine is in operation, the end of said shaft remote from said holder having an operating handle.
- 20 5. A sole edge burnisher comprising a proceeding and receding support, a tool holder movable bodily with said support and rotatable on an axis transverse to the travel thereof, said holder having locking means releasable by axial shifting of said holder, a second and fixed support spaced from the other, and a flexible shaft extending between the two supports and both rotatable and slidable thereon, one end of said 30 shaft being connected to said tool holder

and the other end of the shaft having an operating handle.

6. A sole edge burnisher comprising a proceeding and receding support, a tool holder movable bodily with said support, a 35 shaft section mounted on said support and extending transverse to its travel, one end of said shaft section being connected to said tool holder and the other end thereof having a socket, a bearing mounted rockably 40 at a point spaced from said support, and a second shaft section mounted rotatably in said bearing and having one end received loosely but non-rotatably in said socket, the other end of said second section having an 45 operating handle.

7. A structure as specified in claim 6, said tool holder having locking means releasable by axial shifting of said holder, and said shaft sections being slidably mounted and 50 spring-resisted for so shifting said holder.

8. A structure as specified in claim 6, said socket being widened in one direction to permit the proceeding and receding motion of said tool holder without continually moving 55 said second shaft section.

In testimony whereof I have hereunto set my hand.

OTIS R. ANGELL.
